UNITED STATES PATENT OFFICE.

HUGH DUNN, OF FALKIRK, SCOTLAND.

MACHINE FOR FINISHING BOOK COVERS BY LINING, LETTERING, OR ORNAMENTING.

Application filed June 23, 1926, Serial No. 117,980, and in Great Britain March 13, 1926.

This invention relates to machines for finishing the rounded back of books of miscellaneous sizes and thicknesses by the application of lining, lettering or ornamentation.

The object of this invention is to provide a machine which will effect metallic lining, lettering or ornamenting on the rounded back of books in one operation.

According to this invention the machine comprises means for holding the book, means for lining, lettering and ornamenting the book, means for applying metallic leaf to the book and reciprocable mounting means for said lining, lettering and ornamenting means and said metallic leaf applying means whereby they can be moved over the back of a book, the aforesaid means cooperating to allow the metallic leaf to be laid and impressed upon the back of the book in one operation. In this case also means are provided for heating the tools. The said means for laying on gold is adapted to be detachably mounted on the means carrying the lining, lettering or ornamenting tools.

The particular means for applying the gold comprise two transverse members adapted to be mounted in advance of the lining, lettering or ornamenting tools and parallel therewith, a frame or frames adjustably mounted on said transverse members so that they can be moved into a position in alignment with the lining, lettering or ornamenting tools, said frame or frames being also adjustable in themselves and being adapted to receive means, carrying and adapted to apply gold to the book, of a width equal to or greater than that of the said tools. This frame may be provided with a bush adapted to carry gold leaf (preferably mounted on tissue) in reel form and with a roller rotatably mounted thereon, around which the tissue with the gold leaf on the outer surface thereof can be passed and by which it can be applied to the book by rolling the roller over the latter.

Referring to the drawings:

Fig. 1 is a longitudinal sectional elevation of the machine.

Figs. 2, 3 and 4 are views of a device which can be used for lining, lettering or ornamenting.

Fig. 5 is a fragmentary view showing the

method of positioning the lining, lettering and ornamenting means.

Fig. 6 is a fragmentary view showing the method of detachably mounting the tools.

Figs. 7 and 8 are elevation and plan views respectively of a device for laying on gold leaf.

Fig. 9 is a fragmentary side view illustrating the application of such gold lining device to the machine.

In the particular construction illustrated in Fig. 1 which shows a machine adapted for lettering, the apparatus comprises a rectangular box-like main frame 1, having two clamping members 2-3 adapted to receive and hold the book 4; at least one of which clamping members is movable, preferably under the control of a quick-acting screw 5 operated from a hand wheel 6 on the exterior of the main frame. A setting gauge 7 is provided on the clamping members 65 adapted to position the book in relation to the tools.

On the top of the frame 1, at one end thereof, is fixed two spaced bearings 8 carrying a bar 9 mounted on trunnions 9^a so that the bar serves as a pivot for a flat rectangular guide frame 10. This guide frame extends from one side of the machine across the top of the main frame and is free at its other end 11.

Slidably mounted on the guide frame is a carriage 12 having downwardly extending lugs 13 which project into the main frame and carry a spindle 14 on which is mounted the type carrier hereinafter described. As shown in Fig. 6 the spindle is detachably mounted on the machine by means of the fixed projection 13^a on one side and the movable projection 13^b on the other side engaging in counter sinks 14^a in the spindle. The projection 13^b is mounted on a screw 13^c so that it can be retracted and the spindle 14 thereby readily removed and replaced.

The carriage has a pin and slot connection at each slide thereof with a lever-like frame, the carriage being preferably provided with projecting pins 17 which engage in slots 18 in the frame. This lever frame consists of two bars 19 one at each side of the main frame pivotally mounted at 20. These bars extend upwardly and are provided with a number of transverse rods, of which two marked 21 and 22 are shown, disposed at

different distances from the fulcrum and constituting handles any one of which can be selected by the operator so as to vary the leverage.

5 The guide frame 10 is provided with rearwardly extending spindles 23 carrying counter balance weights 24, which are adjustable thereon, being clamped in their adjusted position by the set screws 24^a, said weights 10 acting to counter-balance the weight of the tool carriage and other parts mounted on said frame.

The carriage with the lining tools is so arranged that it is rocked on the guide frame and thereby moved from one side to the other of the clamping members under the action of the lever frame. When the tools are idle, such as when a book is being placed into the clamping members, preparatory to 15 lining, the tools will lie at one side of the clamping members. In a position, thereof, directly beneath this idle position of the discs a series of gas burners 25 or other suitable heating devices are disposed so as to 20 heat the tools.

In order to regulate the pressure of the lining tools as they move over the book, the free end 11 of the guide frame can be 25 pressed down to the required extent.

30 For applying lettering or ornamenting matter to the back of the book, the device such as is shown in Figs. 2, 3, and 4 is provided. This device consists of a rectangular trough 30 preferably provided on its base with a clamping plate 31 operated by the clamping means 32; the trough and clamping plate being so constructed and arranged as to be firmly fixed upon the spindle 14. This spindle is adapted to be detachably mounted on the frame as hereinbefore explained. The trough 30 is adapted to receive type which is composed therein, an example of such type being indicated in 35 position and marked 35. The type is assembled with the distance pieces 36 and the whole is held securely in the trough by means of the adjustable longitudinal plate 37 and lateral plate 38 operated by the pinching screws 39. The longitudinal plate 40 37 may be dispensed with.

The trough is supported in a position in which it extends downwardly as indicated in Fig. 1 so that by reciprocating the slide 12 on the frame 10 the type contained in the trough is rocked over the back of the book as clearly shown in this figure and in order to ensure that the lining, lettering or other ornamenting matter is placed symmetrically upon books of different thickness, a graduated member 40 is provided having a boss 41 by which it is mounted upon the frame member 10 and fixed by the pinching screw 42, this graduated member co-operating with the front edge 43 of the slide 12, 55 which edge acts as an index mark, to show

the position of the centre of the book for each thickness of book. In the arrangement shown, for instance, a book 2 inches thick is clamped in position and the slide is moved until the edge 43 is opposite the 2 inch mark 70 on the scale when the type will be positioned centrally over the back of the book. In use the type will be positioned in this manner while the frame 10 is in its raised position and subsequently the frame 10 will be depressed to bring the type into contact with the back of the book after which the slide will be reciprocated to rock the type carrier and the type over the back of the book to either side of the central position. 75

It is not essential that the operation be carried out in the manner specified above because, as will be understood, the tools may be rocked over the book commencing at one side and finishing at the other. In fact this method is found preferable in certain circumstances. By employing suitable type, 80 lining or other ornamental matter can be applied.

The means for laying on the gold is shown 90 in Figs. 7 and 8 and the application thereof to the machine is illustrated more clearly in Fig. 9.

The apparatus shown in Figs. 7 and 8 comprises two spaced transverse supporting members 50, 51 and arranged between these transverse members is a number of frames, of which three are shown. These frames each comprise a fixed plate 53 having a series of lugs 54, 54^a mounted thereon and movable plates 55 having slots 56 with which the lugs 54 engage and by which said plates are slidably but otherwise immovably connected with the plates 53. Two screws 57 are provided, which pass through 95 holes in one plate and are screwed to engage with tapped holes in the other plate so that the plates are moved towards or away from each other by rotating the screws. These screws form a support for bushes 58, 59 which serve as distance pieces for the plates, and one of these bushes 58 serves to rotatably support a reel 60 of gold leaf mounted on tissue and the other 59 to support a roller 62 around which the free end of the 100 tissue carrying gold leaf is passed and to which it is secured. The arrangement is such that the gold leaf with its supporting tissue is continuously rolled off the reel on to the roller as the leaf is used and it is so arranged that the position of the gold leaf and its tissue is the reverse of that on the reel, the gold leaf on the roller being situated on the outside with the tissue between the gold leaf and the roller. 105

110 It will be seen that the lugs 54^a engage in slots 61 in the transverse member so that they can be adjusted into any suitable position. Also the plates forming the frame for carrying each reel of gold leaf is adjustable 115 120 125 130

so as to accommodate various widths of gold leaf.

The transverse members 50, 51 are fixed upon the carriage 12 of the machine in the position shown in Fig. 8 by means of the clamping plates 63.

One or more of these sets of plates will be provided according to the work.

In practice the individual elements for laying the gold will be adjusted to a position in the plane of the movement of the lining, lettering or ornamenting tools and these elements are rocked over the back of the book in advance of the said tools when the roller 15 having the gold leaf on its outer surface is brought against the back of the book and as the elements are moved the roller will rotate in contact with the book and will cause it to lay a strip of gold leaf on the 20 back of the book, and subsequently the said tools which have been sufficiently heated are moved over the said strip of gold leaf and serve to impress the back of the book with the shape or pattern of the tools, after which 25 the surplus gold leaf can be removed in the usual way.

Having now fully described my invention, what I claim and desire to secure by Letters

Patent is:—

30 1. A machine for the purpose specified, comprising, in combination, means for holding the book, means for lining, lettering and ornamenting the book, means for applying metallic leaf directly to the book and reciprocable mounting means for said lining, lettering and ornamenting means and said metallic leaf applying means whereby they can be moved over the back of a book, the aforesaid means co-operating to allow the 35 metallic leaf to be laid on the back of the book and subsequently impressed upon the back of the book in one operation.

2. A machine for the purpose specified, comprising, means for holding the book, 45 means for lining, lettering and ornamenting the book, means for applying metallic leaf directly to the book, reciprocable means for mounting said lining, lettering and ornamenting means, means pivotally mounted at 50 one end and extending across the machine above said book holding means and being manually operable at its free end for moving the means for lining, lettering and ornamenting towards the book during the reciprocation thereof so that the pressure exerted on the lining, lettering and ornamenting means and on the metallic leaf applying means can be suited to the work, the aforesaid means co-operating to allow the 55 metallic leaf to be laid on the back of the book and subsequently impressed on the back of a book at a single operation.

3. A machine for the purpose specified, comprising, a stationary device for holding 60 the book, means for lining, lettering and

ornamenting, means for applying metallic leaf directly to the back of the book, means rockably mounting both the lining, lettering and ornamenting means and the metallic leaf applying means adapted to move the 70 said means successively over the book holding means from a position at one side to a position at the other side thereof, a stationary heating device disposed at one side of the book holding means in a position beneath the said lining, lettering and ornamenting means when this is in its terminal position at the corresponding side of the book holding means so that the said lining, lettering and ornamenting means is heated 75 while it is idle and is maintained in a heated condition ready for immediate use, the aforesaid means co-operating to allow the metallic leaf to be laid on the back of the book and subsequently impressed on the back of 80 the book in one operation.

4. A machine for the purpose specified, comprising, in combination, means for receiving and holding the book in a fixed position, means to receive lining, lettering and 90 ornamenting means; a manually operable frame pivoted at one side of the machine extending across the book holding means and movable towards or away therefrom, means for reciprocably mounting said receiving means on said frame; means for applying metallic leaf mounted on said frame, and means for moving the gold leaf applying means and said lining, lettering and ornamenting means successively over the back of the book, the aforesaid means co-operating 95 to allow the metallic leaf to be laid directly on the back of the book and subsequently impressed upon the back of the book in one operation.

5. A machine for laying metallic leaf on the rounded back of books, comprising, in combination, book holding means, metallic leaf carrying devices, and rockable mounting means for said metallic leaf carrying devices, adapted to allow said devices to be moved over the back of the book from one side to the other, to apply the metallic leaf thereto.

6. A machine for laying metallic leaf on the rounded back of books, comprising, in combination, book holding means, metallic leaf carrying devices, supporting members detachably receiving said metallic leaf carrying devices, and rockable mounting means 110 for said supporting members, adapted to allow said devices to be moved over the back of the book from one side to the other, to apply the metallic leaf thereto.

7. A machine for laying metallic leaf on the rounded back of books, comprising, in combination, book holding means, rockable members movable angularly in relation to said book holding means, spaced transverse members mounted on said rockable mem- 115

- bers, extending above said book holding means and movable by said rocking members over the back of the book, and frames detachably and adjustably mounted on said transverse members and movable thereby over the back of the book, means on each of said frames for rotatably mounting a reel of metallic leaf so that it can be drawn off said reel, and means actuated on movement over the back of the book for winding said leaf off said reel and applying it directly to the back of the book.
8. A machine for laying metallic leaf on the rounded back of books, comprising, in combination, book holding means, rockable members, movable angularly in relation to said book holding means, spaced transverse members mounted on said rockable members, extending above said book holding means and movable by said rocking members over the back of the book, and frames detachably and adjustably mounted on said transverse members and movable over the back of the book, means on each of said frames for rotatably mounting a reel of metallic leaf so that it can be drawn off said reel, and a roller rotatably mounted on said frames and actuated on movement over the back of the book for winding said leaf off said reel and applying it directly to the back of the book.
9. A machine for laying metallic leaf on the rounded back of books, comprising, in combination, book holding means, rockable members movable angularly in relation to said book holding means, spaced transverse members mounted on said rockable members, extending above said book holding means and movable by said rocking members over the back of the book, and metallic leaf carrying frames mounted on said transverse members, each frame comprising a fixed plate adapted to be detachably and adjustably mounted on said transverse members, a movable plate carried by the fixed plate and co-operating therewith to allow a reel of metallic leaf to be mounted thereon, means extending between said plates for rotatably mounting said reel so that the leaf can be drawn off said reel and means rotatably mounted between said plates and actuated by the movement thereof over the back of the book for winding said leaf off said reel and applying it directly to the back of the book.
10. A machine for laying metallic leaf on the rounded back of books, comprising, in combination, book holding means, rockable members movable angularly in relation to said book holding means, spaced transverse members mounted on said rockable members, extending above said book holding means and movable by said rocking members over the back of the book, and metallic leaf carrying frames mounted on said

transverse members and movable thereby over the back of the book, each frame comprising a fixed plate, lugs on said plate adapted to detachably and adjustably fix said plate to said transverse members, a movable plate carried by the fixed plate and co-operating therewith to allow a reel of metallic leaf to be mounted thereon, means extending between said plates for rotatably mounting said reel so that the leaf can be drawn off said reel and means rotatably mounted between said plates and actuated by the movement thereof over the back of the book for winding said leaf off said reel and applying it directly to the back of the book.

11. A machine for laying metallic leaf on the rounded back of books comprising, in combination, book holding means, metallic leaf carrying devices, means for rocking said devices over the back of the book and vertically movable supporting means for said devices adapted to allow the devices to maintain contact with the arcuate back of the book as they are moved over the latter.

12. A machine for laying metallic leaf on the rounded back of books comprising, in combination, book holding means, metallic leaf carrying devices, supporting members carrying said devices, vertically movable supporting means for said supporting members and means for rocking said supporting members to move said devices over the book.

13. A machine for laying metallic leaf on the rounded back of books comprising, in combination, book holding means, supporting members extending transversely above said book holding means, metallic leaf carrying devices detachably and adjustably mounted on said supporting members, vertically movable supporting means for said supporting members and means for rocking said supporting members to move said devices over the back of the book.

14. A machine for laying metallic leaf on the rounded back of books comprising, in combination, book holding means, supporting members extending transversely above said book holding means, frames carried by said supporting members, two spaced sleeves carried by each of said frames, one of which is adapted to receive a reel of metallic leaf and the other carrying a roller adapted automatically to take the leaf from the reel and lay it on the surface over which it moves, vertically movable supporting means for said supporting members and means for rocking said supporting members to move said frames over the back of the book.

15. A machine for laying metallic leaf on the rounded back of books comprising, in combination, book holding means, supporting members extending transversely above said book holding means, frames carried by said supporting members, two spaced sleeves

carried by each of said frames, one of which is adapted to receive a reel of metallic leaf and the other carrying a roller adapted automatically to take the leaf from the reel and lay it on the surface over which it moves, vertically movable supporting means for said supporting members, means for

10 said frames over the back of the book, and means for adjustably and detachably mounting said frames on said supporting members said means being also adapted to retain the frames in their adjusted positions.

In testimony whereof I affix my signature.

HUGH DUNN.
